US00D954996S

(12) **United States Design Patent** (10) **Patent No.:** **US D954,996 S**
Motadel et al. (45) **Date of Patent:** **** Jun. 14, 2022**

(54) **PIPETTE TIP TRAY**

(71) Applicant: **BIOTIX, INC.**, San Diego, CA (US)

(72) Inventors: **Arta Motadel**, San Diego, CA (US);
Peter Paul Blaszczak, San Diego, CA (US);
Kyle Richard Briggs, San Diego, CA (US)

(73) Assignee: **BIOTIX, INC.**, San Diego, CA (US)

(**) Term: **15 Years**

(21) Appl. No.: **29/735,633**

(22) Filed: **May 22, 2020**

Related U.S. Application Data

(63) Continuation of application No. 29/642,485, filed on Mar. 29, 2018, now Pat. No. Des. 882,280.

(51) **LOC (13) Cl.** **24-02**

(57) **CLAIM**

The ornamental design for a pipette tip tray, as shown and described.

DESCRIPTION

FIG. 1 is a top perspective view of a pipette tip tray showing the claimed design;

FIG. 2 is a bottom perspective view thereof;

FIG. 3 is an enlarged perspective view of area 3 circled in FIG. 2;

FIG. 4 is a top view thereof;

FIG. 5 is a bottom view thereof;

FIG. 6 is a front view thereof;

FIG. 7 is back view thereof;

FIG. 8 is a side view thereof; and,

FIG. 9 is another side view thereof.

1 Claim, 8 Drawing Sheets
